(57) **CLAIM**

The ornamental design for a collapsible tent, as shown and described.

DESCRIPTION

FIG. 5.1 is top view of a collapsible tent according to my new design, the collapsible tent is shown in a fully folded state;

FIG. 5.2 is a front view thereof;

FIG. 5.3 is a rear view thereof;

FIG. 5.4 is a left side view thereof;

FIG. 5.5 is a right side view thereof;

FIG. 5.6 is a top, rear, left perspective view thereof; and

FIG. 5.7 is a top, rear, right perspective view thereof.

The bottom view of the collapsible tent of FIG. 5.1, which is not disclosed in the drawings, forms no part of the claimed design.
